(57) CLAIM

The ornamental design for a cookie, as shown and described.

DESCRIPTION

FIG. 1 is a perspective view of a cookie showing our new design;

FIG. 2 is a top view of the design shown in FIG. 1;

FIG. 3 is a bottom view of the design shown in FIG. 1;

FIG. 4 is a right side view of the design shown in FIG. 1;

FIG. 5 is a left side view of the design shown in FIG. 1;

FIG. 6 is a front view of the design shown in FIG. 1; and,

FIG. 7 is a rear view of the design shown in FIG. 1.

The broken lines shown in the drawings are for the purpose of illustrating unclaimed portions of the cookie and form no part of the claimed design.

1 Claim, 2 Drawing Sheets
